UNITED STATES PATENT OFFICE.

HAROLD AUGUSTINE TOLLEY GUEST, OF BIRMINGHAM, ENGLAND.

HOLDER FOR THE BURNING OF CANDLES.

1,365,485.

Specification of Letters Patent. Patented Jan. 11, 1921.

Application filed June 5, 1920. Serial No. 386,732.

To all whom it may concern:

Be it known that I, HAROLD AUGUSTINE TOLLEY GUEST, subject of the King of Great Britain, residing at 44 Drayton road, Kings 5 Heath, in the city of Birmingham, England, insurance agent, have invented certain new and useful Improvements in Holders for the Burning of Candles, of which the following is a specification.

10 The invention relates to holders for the burning of candles of the kind described in the specifications of my prior British Letters Patent Nos. 134475 and 134583, that is to say, in which the candle is pushed up to 15 a shoulder in a tubular piece carrying at its upper end an overflow cup for wax, or the like, and a plug slidably fits within the tubular piece to provide by its upper end a stationary support for the lower end of the 20 candle during the burning, at which time said tubular piece bodily and gradually falls.

The invention uses a single overflow cup at the upper end of the tubular piece, carries centrally thereof the side walls of a shallow upwardly extending socket the bottom of which is provided by the upper end of the plug, and perforates or provides holes through said side walls to drain the wax 25 from the cup into the socket, particularly when the last bit of candle is being burnt, at which time the upper end of the plug provides the bottom to the socket.

The invention is represented by the drawing, 30 35 which is a vertical section of the parts of the holder in the positions they would assume if a short length of candle was inclosed therein.

The bottom d^3 of the socket d is formed 40 by the upper end of a central plug i over which a tubular piece j slidably fits to carry at its upper end the overflow cup c and the side walls of the socket d through which the drain holes d^2 are provided. The candle is 45 inserted up the tube j so that its burning end projects to the upper edge of the socket d and so that its lower end rests against the upper end d^3 of the plug, which is suitably supported by the base part l of the candle 50 holder.

The tube j and its cup c and socket walls rest upon the burning edge of the candle as a weight, and as the candle burns away, supported always by the plug i , this tube 55 j gradually falls until on the burning of

the last piece of candle the upper end d^3 of the plug provides a closing bottom to the socket d , so that the melted wax flowing from the cup into the socket during the burning of the last bit of candle cannot escape from said socket. 60

Air holes such as m may be provided through the walls of the tube j to keep cool the walls of the socket d until the burning of the last bit of candle, when said air holes are closed to said socket by moving over the plug i and preferably into an external tube n rigidly supported from the base l of the candle holder, the idea of the air holes m being to prevent the overflow wax becoming 70 melted until the burning of the last bit of candle. 75

It will be seen that the interior walls d^4 of the socket d are slightly tapering with the upper edge i^2 of the plug i inclined to suit. The effect of this slight taper is that during 80 normal burning the upper end of the candle is so softened by the heat as to cause said upper end to normally project approximately level with the upper edge of the socket. 85

Having now described my invention what I claim and desire to secure by Letters Patent is:—

1. In a candle holder, a base having a 85 tube secured thereto, a plug mounted within said tube, a vertically movable tube adapted to automatically slide between said plug and stationary tube as the candle burns, said movable tube having a tapered portion 90 provided with a plurality of apertures formed therein, an overflow cup secured to said movable tube near the upper end thereof adapted to communicate with the interior of said movable tube through said apertures, said movable tube being also provided with a series of openings adjacent said overflow cup for preventing the overflow of wax from becoming melted until the candle has burned sufficiently for said plug 95 to cover said openings when the overflow may be melted and burned by the last bit of the burning candle. 100

2. In a candle holder, a tube adapted to receive the candle and move downward automatically as the candle burns, a plug mounted within said tube for supporting the candle, a cup secured near the upper end of said tube for receiving the overflow of melted wax, means for restoring and main- 105 110

taining said overflow in solid condition until said plug approaches the top of the tube, an extension on said tube projecting beyond the cup, said extension being provided with apertures whereby the wax within said cup may finally have access to the burning wick of the candle.

In testimony whereof I have hereunto set my hand in presence of two subscribing witnesses.

HAROLD AUGUSTINE TOLLEY GUEST.

Witnesses:
